COMBINED LABEL PRINTING AND DISPENSING IMPLEMENT

Herbert H. Loeffler, 210 Clinton Ave.,
Brooklyn, N.Y. 11205

Filed Feb. 28, 1966, Ser. No. 1,210

Term of patent 14 years

(Cl. D64—10)

Fig. 1

Fig. 2

Fig. 3

Fig. 4

Fig. 5

FIG. 1 is a perspective view taken from one side of a combined label printing and dispensing implement showing my new design.

FIG. 2 is a perspective view taken from the side opposite that shown in FIG. 1;

FIG. 3 is a front elevational view thereof;

FIG. 4 is an elevational view of the side shown in FIG. 2; and

FIG. 5 is a bottom plan view thereof.

This application is a continuation-in-part of Ser. No. D.82,063 filed Oct. 7, 1964 now abandoned.

I claim:

The ornamental design for a combined label printing and dispensing implement, substantially as shown and described.
